CONVERTED HOUSE CAR

Frank Ditchfield, Cleveland, Ohio, assignor to
The Youngstown Steel Door Company, Cleve-
land, Ohio, a corporation of Ohio

Application December 17, 1932, Serial No. 647,761

4 Claims. (Cl. 105—409)

This invention relates to improvements in converted house car.

At the present time there are many thousands of wood sheathed box cars owned by various railroads, which box cars were built several years ago. These box cars were originally provided with heavy metal underframes, metal ends but wooden posts, braces and side plates, certain of them having the wood posts reinforced by metal beams. These wood sheathed cars, after years of service, are badly deteriorated and present a difficult problem to the railroads in the matter of maintenance or complete scrapping. The metal underframes and the metal ends and the wooden framework proper of the superstructure are still, on the average, suitable for continued service. The railroads, however, desire metal sheathed cars. To replace the wood posts, braces and side plates with all steel side plates, posts and braces to which to rivet sheet metal sheathing, would involve quite heavy costs. Neither is it practical to directly attach steel sheathing to wood side plates, posts and braces in a manner that will transfer any appreciable part of the weight of the metal sheathing thereto through the attaching means since this would result in unavoidable leakage and the constant vibration in service would soon work the attaching means loose in the wood with consequent ultimate failure of the whole car superstructure.

One object of this invention is to provide a metal sheathed car converted from a wood sheathed car wherein the original wood frame elements may be reclaimed and retained without any impairment of their efficiency or functions and wherein also the attachment of the outer metal sheathing is made in such manner as to form a stronger and more rigid superstructure than before and having greater life.

Another object of this invention is to provide a metal sheathed car of the house type having a metal underframe and superstructure framework of wood elements so arranged that substantially the entire dead weight of the metal sheathing is transferred directly to the metal underframe and the attaching means between the metal sheathing and wood elements are relieved of any appreciable weight-carrying function.

More specifically, an object of this invention is to provide a metal sheathed house car wherein the metal sheathing replaces former wood sheathing while retaining the original superstructure frame elements and over-all width dimensions, the construction being such that a minimum of labor is required in making the conversion and

the resulting converted car has a more rigid superstructure than originally.

Still another specific object of the invention is to provide a converted car of the type above indicated wherein the metal sheathing replacing the prior wood sheathing is so applied as to avoid any necessity for counter-boring the wood posts for accommodation of the rivet heads and wherein the metal sheathing may be fabricated complete prior to application to the superstructure framework.

Other objects of the invention will more clearly appear from the description and claims herein-after following.

In the drawings forming a part of this specification, Figure 1 is a side elevational view of approximately half of a converted box car showing the improvements incorporated therein, parts being broken away in order to better accommodate the view on the sheet. Figure 2 is an enlarged vertical, sectional view corresponding to the line 2—2 of Figure 1, parts being broken out to accommodate the view on the sheet. Figures 3, 4 and 5 are detail horizontal, sectional views corresponding to the lines 3—3, 4—4 and 5—5 respectively of Figure 1. And Figure 6 is a detail sectional view similar to the lower portion of Figure 2 to illustrate certain details of construction of the wood sheathed car prior to being converted by the improvements herein described.

In said drawings, it has been deemed necessary to illustrate only approximately one half of one side of the car, it being understood that the arrangement shown in Figure 1 will be duplicated at the opposite side of the door opening and the same arrangement provided on the opposite side of the car. The car, as shown, comprises a metal end 10 which may be of any one of the well known forms of commercial ends now on the market; a metal underframe including channel side sills 11; a top wood side plate 12; carline 13; roof 14; wood door post 15; intermediate side posts 16—16; diagonal wood braces 17—17; corner wood posts 18; wood flooring 19; and inner wood lining 20. As shown, referring particularly to Figure 4, the intermediate wood posts 16 are braced by channel beams 21 secured thereto and the posts and braces are seated at their ends in suitable base or pedestal castings 22. The parts so far specifically designated by reference characters are or may be such as incorporated in the original wood sheath box or house car prior to being converted to the metal sheathing and all said parts, as will be evident, remain in their

original positions and perform their original functions.

Referring to Figure 6, the box car prior to conversion, is shown as having the usual outer wood sheathing 23 extended down below the floor 119 beneath which is disposed a wood stringer 24 supported at longitudinally separated intervals by short angle irons 25 riveted to the side sill 111, the lower ends of the outer sheathing boards being retained by a longitudinally extending angle 26 bolted through the sheathing boards, stringer 24 and side sill 111.

In making the conversion to the steel sheathing, the outer sheathing boards 23 and angles 26, stringers 24 and angles 25 are not only taken off but discarded. Temporarily, also, the corner post 18 is taken out as well as the inner lining 20 but are later replaced and used as shown in Figures 1 to 5.

In carrying out the invention, the sheet metal, preferably steel, outer sheathing designated generally by the reference character A, is made up of a series of panels 27-28-29. A plurality of such panels sufficient to cover that portion of the side wall extending from a door post to the corner, are cut to the proper size and the same riveted together along vertical adjacent overlapped edges, as indicated by the series of rivets 30-30. Also, preferably prior to application to the car structure, the riveted assembly of the panels has secured thereto along its upper edge, a Z-bar 31 riveted by the horizontal series of rivets 132. Also preferably before application to the car structure, the panel assembly has secured thereto along its bottom edge another heavier Z-bar 32 as by the horizontal series of rivets 33. Similarly, there is secured to the vertical edge of the panel assembly to be associated with the door post, a slightly offset plate 34 as by the series of rivets 35. The Z-bar 31 and plate 34 are provided with holes at suitable spaced intervals for the accommodation of bolts, as indicated at 36 and 37 respectively, and the inner depending flange of the Z-bar 32 is punched at suitable intervals to accommodate the rivets 38-38. It will also be understood that the wood side plate 12, and door post 15 are, in the meantime, suitably bored for the reception of the bolts 36 and 37; and the side sill 11 drilled for reception of the rivets 38. Also, the intermediate posts 16 are bored at suitable spaced intervals for the reception of shoulder bolt rivets 39-39 and the latter set in place. Each of said shoulder bolt rivets 39 comprises a main shank 40 extending through the post and threaded at its inner end for the reception of a nut 41; an integral annular shoulder or boss 42 engaging against the outer surface of the post, and an initially outwardly extended rivet shank 43, indicated by dotted lines in Figure 2. After the bolt rivets 39 have been set in place and the panel assembly having been provided with suitable openings in the riveted lap joints to correspond with the location of the bolt rivets, the assembly is then placed in position, the Z-bar 32 riveted to the side sill 11, the upper Z-bar 31 bolted by the bolts 36 to the side plate, and the offset plate 34 bolted to the door post by the bolts 37. As will be apparent, the plate 31 provides a weather sealed joint or connection between the upper edge of the sheathing and side plate; the Z bar 32 a similar connection between the lower edge of the sheathing and side sill and the plate 34 a similar connection between the sheathing and door post. At the same time,

it is obvious that the rivet shanks 43 will be entered through the corresponding openings of the panel assembly after which the rivet shanks 43 are then upset and the heads formed, the bolt rivets being suitably bucked at their inner ends during this process. The vertical end edge of the panel assembly is also connected to the vertical edge flange 47 of the metal end 10 as by the vertical series of rivets 48, access on the inner side for the bucking up tool being possible because of the temporary removal of the corner post 18. After the metal sheathing has been secured in place as described, the corner post 18 may then be replaced and also the inner lining 20, as well as the vertical tie bolts 49 which will also have been previously removed, the lower ends of said tie bolts now being secured to the horizontal web of the Z-bar, as best shown in Figure 2.

With the construction shown and described, it is evident that substantially the entire weight of the metal sheathing assembly is transferred to and sustained by the lower Z-bar 32, which in turn is rigidly and permanently connected to the side sill 11 of the underframe, thus relieving all the wood frame elements of the superstructure from any appreciable load, the various bolt attaching means thereto functioning primarily to retain the sheathing assembly in place. In this manner, the several series of bolts 39, 36 and 37 are substantially entirely relieved of any weight-sustaining function and hence will not wear loose in their respective wood element supports. It will also be noted a strong riveted connection is provided between the panel structure and the metal end wall which, in conjunction with the other connections of the metal sheathing to the superstructure frame elements and side sill will constitute a very much more rigid superstructure and one less subject to weaving than the original wood sheath construction. Attention is further called to the shoulder bolt rivets 39 which not only provide an exceedingly cheap and efficient manner of attaching to the posts and eliminate any necessity for counter-boring the posts for reception of the heads of the rivets 39, but additionally insure that the metal sheathing shall be located in the proper plane to maintain the original over-all width of the car. This will be evident from comparison of Figures 2 and 6 where it will be seen that, by use of the spacing shoulders 42 on the bolt rivets 39, the metal sheathing is held in a plane to compensate for the difference in thickness of the metal sheathing and the original wood sheathing 23. A corner gusset 50 is also preferably riveted to the end wall 10 and upper end corner of the metal side sheathing, as indicated in Figure 1, to further strengthen the assembly against weaving.

After the metal sheathing has been applied as above described, the inner wood lining 20 may be replaced as well as the grain shedding strips 51 where the latter are to be employed.

In the foregoing, only one half, that is, from door post to corner post of the side wall of the car has been referred to specifically but, as will be understood, the structure will be duplicated for the remaining side wall portions of the car.

From the preceding description, it will be seen that all of the metal parts may be manufactured at relatively small expense and fabricated either at the mills or at the car repair shops prior to application to the car. Furthermore, the railroads are enabled to salvage the greater and still remaining usable parts of those old wood sheathed

cars now in service and which are rapidly failing and, at the same time, obtain a car with a stronger and more serviceable superstructure than originally.

5. Although the improvements herein shown and described are now considered the preferred manner of carrying out the invention, the same is by way of illustration only and not by way of limitation, and all changes and modifications coming 10 within the scope of the appended claims are contemplated.

What is claimed is:

1. A house car having an underframe including a metal side sill; a superstructure framework 15 including wood posts and side plate, the posts being disposed outwardly of the plane of the side sill; an outer sheet metal side sheathing disposed in a plane outwardly of the intermediate posts; means for attaching the upper and lower edge 20 portions of said sheathing to the side plate and sill and providing weather sealed connections therewith, respectively; and spacing and attaching means for fastening said sheathing to the intermediate posts in spaced relation to the outer 25 sides thereof.

2. A house car having an underframe including a metal side sill; a superstructure framework including wood posts and side plate; an outer sheet metal side sheathing; means for attaching 30 the upper and lower edge portions of said sheath-

ing to the side plate and sill, respectively; and spacing and attaching means for fastening said sheathing to the intermediate posts in spaced relation to the outer sides thereof, said spacing and attaching means comprising shoulder bolt rivets with the shoulders thereof interposed between the posts and sheathing.

3. A house car having an underframe including a metal side sill; a superstructure framework including wood posts and side plate; an outer sheet metal sheathing; a flanged bar riveted to the side sill and to the lower edge of the sheathing; a metal plate riveted along the top edge of the sheathing and secured to the side plate, said bar and metal plate constituting weather sealing means; and means for retaining the sheathing in outwardly spaced relation to the posts.

4. A house car having an underframe including a metal side sill; a superstructure framework including wood posts and side plate; an outer sheet metal sheathing; a flanged bar riveted to the side sill and to the lower edge of the sheathing; a metal plate riveted along the top edge of the sheathing and secured to the side plate; and means for retaining the sheathing in outwardly spaced relation to the posts, said means including shoulder bolt rivets riveted to the sheathing and bolted to the posts with the shoulders interposed between the posts and sheathing.

FRANK DITCHFIELD. 30
